UNITED STATES PATENT OFFICE

172,113

COSMETIC TRAY

Norman L. Smith, Alexandria, Va.

Application December 24, 1953, Serial No. 28,200

Term of patent 14 years

(Cl. D86—10)

To all whom it may concern:

Be it known that I, Norman L. Smith, a citizen of the United States, residing in Alexandria, Virginia, have invented a new, original, and ornamental Design for a Cosmetic Tray, of which the following is a specification, reference being had to the accompanying drawing, forming a part thereof.

Fig. 1 is a top plan view of a cosmetic tray, showing my new design;

Fig. 2 is a side elevational view thereof; and

Fig. 3 is a partial perspective view of the underside of said tray.

I claim:

The ornamental design for a cosmetic tray, as shown.
